UNITED STATES PATENT OFFICE

GEORGE F. PAWLING, OF PHILADELPHIA, PENNSYLVANIA, ASSIGNOR, BY MESNE ASSIGNMENTS, TO SARAH BELLEVUE PAWLING, OF GLENDALE, PENNSYLVANIA

BUILDING CONSTRUCTION

Application filed September 30, 1927. Serial No. 223,146.

This invention relates to building construction, and is particularly applicable for use in applying plastic coatings to girders, joists, or columns, and it has especial reference to a system of fireproofing with gypsum.

As is now pretty generally recognized in the art, gypsum is an excellent fireproofing material, but it has not come into as extensive use as its merit in this respect warrants, primarily for the reason that it lacks somewhat in structural strength and is liable to be melted off under the action of the heat or washed off under the high pressure streams 15 of water commonly used in fighting fires.

With the foregoing in mind, my invention contemplates for one of its principal objects the provision of a system of building construction in which it is possible to use to 20 the fullest extent the undoubted merit of gypsum as a fireproofing. In carrying out my invention I provide means for applying what I have termed "armored gypsum" to girders, ceilings and columns.

More specifically stated, my invention has 25 for an object the provision of an improved self centering form which acts as reinforcement as well as form, and which can be applied with equal readiness to joists, girders or columns, and by my improvements I entirely do away with the necessity for supplementary wooden forms or supporting shoring.

It is also an object of the invention to provide 30 an improved form plate which can be assembled in one plane preferably horizontal on the floor or upon some suitable table, and then subsequently raised and secured directly in the position which it will ultimately occupy in the finished construction. Where flat ceilings are concerned, my improved form will, of course, be applied in its flat condition, just as it was assembled, but where it is to be applied to a girder or a 45 column or some other characteristically formed structural member, it is first bent after assembly to the shape desired and then secured in position adjacent the member which is to be coated or fireproofed.

A further object of the invention is to

provide a system of the character described which is exceedingly simple, inexpensive to manufacture, and economical to use, and one in which the various steps can be performed by unskilled labor.

Other objects and advantages will be pointed out hereinafter in connection with the following description of the accompanying drawings which illustrate preferred embodiments of the invention, and in which—

Fig. 1 is a cross section through a floor and ceiling construction illustrating most of the features of the invention.

Fig. 2 is a section on the line 2—2 of Fig. 1.

Fig. 3 is a section on the line 3—3 of Fig. 1.

Fig. 4 is a plan view on an enlarged scale of a section of my improved form illustrating the formation of the metal lath or form plate and the manner in which adjacent lengths of the metal lath or form plates and furring strips are joined together and the manner in which the plates and the furring are secured together.

Fig. 5 is a section on the line 5—5 of Fig. 4 which shows, in addition, the means which I prefer to use in supporting the form where it occupies a generally horizontal position and the manner in which the plastic material incorporates itself with the form structure.

Fig. 6 is a vertical section on an enlarged scale taken longitudinally of the furring strips and showing in greater detail the manner in which the metal lath or form plate is secured to the furring.

Fig. 7 is a diagrammatical perspective of a section of a form in its flat condition preparatory to being bent into the shape necessary to fit a supporting beam or girder.

Fig. 8 shows the form of Fig. 7 in its bent position.

Fig. 9 is a diagrammatic illustration of the manner in which a flat form is prepared and bent for application to a rectangular supporting column.

Fig. 10 shows the form of Fig. 9 in the condition it assumes when applied to a column, and

Fig. 11 is a cross section through a supporting column illustrating the manner in

which the form is positioned with respect to the column and showing the fill of plastic material or gypsum, together with the coating of plaster on the outside.

Referring to the drawings, it will be seen that my improved form comprises metal lath form plates 1 and furring 2. The metal lath comes in sheets or strips, the edge portions 3 of which are designed to overlap as shown most clearly in Figs. 4 and 6. At intervals along these overlapping portions I slit the material of the lath to form opposed tongues 4, the tongues on one section of the lath overlapping the tongues on the other section. By bending the overlapping tongues backwardly on themselves as shown in Figs. 4 and 6, adjacent sections of the plates 1 are secured together. This is shown in greater detail in my Patent No. 1,574,304, issued February 23, 1926, to which reference may be had, if desired.

The furring strips 2 are U-shaped in cross section as clearly indicated in Fig. 5, the base portion of the U being provided with a plurality of downwardly and horizontally extending clips 5 which are formed by slitting the metal of the furring strip on all but one end of such a clip, and then bending the material first downwardly and then horizontally, as most clearly shown in Fig. 6. These clips are adapted to be engaged beneath the upstanding loops 6 formed in the body of the metal lath. This appears most clearly in Figs. 4, 5 and 6.

In order to provide for continuous lengths of furring from one end of a ceiling to another, for example, I provide each section of furring with a socket portion 7 at one end and a tongue 8 at the other, which sockets and tongues can be easily provided for by simply deforming the metal of the furring strip. The furring strip as described is disclosed and claimed in my Patent No. 1,625,865, issued April 26, 1927, to which reference may be had if desired.

It will be noted that the loops 6 in the metal lath or form plates 1 are arranged in rows between which are ribs or corrugations 6a with the concave side downwardly, as appears very clearly in Fig. 6. This provides for an alternation of loops and corrugations all the way across a ceiling. Furthermore, the overlapping edges 3 of adjacent sections of the form plates are likewise provided with the corrugations 6a.

In preparing a form for a section of ceiling as shown in Figs. 1, 3 and 5, the metal lath is first laid out flat in a horizontal position, either on the floor below, or upon some suitable table with the loops 6 uppermost. The furring strips are then applied by sliding them longitudinally so as to engage the clips 5 beneath the loops 6. A form so prepared is then raised in any suitable manner to the position which it is to occupy beneath

the joists 9 and is then supported from the joists by means of hangers 10, each of which has a hook-like portion 11 at the top adapted to embrace the upper T-shaped cord 12 of the joist in the manner indicated in Figs. 1 and 3. At the bottom each hanger 10 is additionally provided with a similar but smaller hook 13 adapted to pass under and around the furring strips 2, as shown in Figs. 1, 2, 3 and 5, but most clearly in Fig. 5. In this way it is easy to maintain the ceiling form at its proper elevation throughout the length of the joists because at each point of support, the hanger extends downwardly from the top cord of the joist and the top cord is, of course, fixed as to its location.

After the ceiling form has been put in place as described, the plastic gypsum 14 is poured thereon from above. The gypsum flows under and around the loops 6 and over and around the furring strips and the lower ends of the hangers 10, so that such parts of the structure become intimately bound up or incorporated in the gypsum, the metal lath constituting a reinforcement or armor for the gypsum, as well as a form during the pouring operation. The customary coat of plaster 15 may be applied to the under surface of the form.

In this way it will be seen that I have provided a fireproofing material which I have called "armored gypsum" because the metal lath is formed and incorporated in the gypsum in such a way as to protect the gypsum from the action of heat or water. As is well understood in this art, gypsum becomes fluid at high temperatures, so that it will gradually drip off under the action of the fire aided by the washing action of the high pressure streams of water which may be applied against it. This has constituted one of the difficulties heretofore encountered in the use of gypsum as a fireproofing, but by my improvements these difficulties are entirely overcome, since the metal lath prevents the gypsum from dripping or sloughing off in case of fire.

I wish to direct attention to the fact that in case of fire the comparatively thin coating of plaster 15 blows off, thus exposing the metal of the form plate to the action of the heat so that considerable expansion of the form plate occurs and must be taken care of in order to maintain perfect contact with the gypsum above and prevent any loss. This is accomplished by virtue of the corrugations 6a and the loops 6 in alternation across the ceiling. I prefer to place the corrugations approximately upon $\frac{7}{8}$ " centers and the loops upon $1\frac{1}{8}$ " centers staggered in adjacent rows. The action which takes place under the expansion of the heat is somewhat as follows: The metal, of course, expands, but the expansion is completely taken care of in one direction by the corrugations and in the op-

posite direction by the loops. Therefore, the expansion of the form plate as a whole is accommodated throughout in small localized areas and no buckling results. This is important because buckling would have a tendency to draw the plate away from the gypsum whereas, with the construction which I employ, this is not possible and the gypsum is at all times well protected or armored. By virtue of this construction the relative motion between the plate and the gypsum is, for all practical purposes, a negligible factor.

Where a supporting girder or beam 16 is encountered I first assemble a section of metal lath 1 in a horizontal position as indicated in Fig. 7, and then apply thereto the furring strips 2a in the manner already described and indicated diagrammatically in Fig. 7, which strips may be especially notched out as at 17 so that the form, as a whole, may be readily bent into the position shown in Fig. 8, and then applied to the girder 16, as shown in Figs. 1 and 2.

The girder form so prepared and placed in position is then supported similarly to the manner in which the ceiling form is supported, except that the hangers 18 are of an inverted U-shape so that they may be passed over the top of the girder 16 from which they are suspended. The end of each leg of the U-shaped hangers 18 is provided with a hook 19 which passes beneath and around the furring 2a. At each side of the girder the lath of the girder form may be bent over as at 20 to meet the lath in the ceiling form, as shown in Fig. 1.

In order to properly position the girder form, I prefer to use supplemental strips 21 which may be made, if desired, from a section of a furring strip placed in inverted position (see Figs. 1 and 2) and held in place on the lower flanges of the girder 16 by means of the bent metal pieces 22. The bent metal pieces may be secured to the strip 21 in any desired manner, and before application of the strip, the pieces 22 project vertically upward, and after application they are bent around to embrace the flanges of the girder 16 as shown in Fig. 1. The ends of the strips 21 are embraced by the furring strips as at 21a. This provides a simple yet firm positioning means for the girder form.

After the girder form is in place, the gypsum 14 is poured from above the pouring operation, as a matter of fact taking place at the time that the ceiling is poured, as already described, it being understood, of course, that all of the forms for a given area or section of the ceiling are in place when pouring operations are being conducted.

The same idea is carried over into the fireproofing of supporting columns, the form of Fig. 9 having been laid out in horizontal position prior to the bending operation. Here the furring strips 2b must be provided

with four notched out places 17a in case of a rectangular or square column, such as illustrated in Figs. 9 to 11 inclusive.

After the form is bent to the position shown in Fig. 9, it is applied to the column 23 of Fig. 11, and then the bending is completed so that the form will enclose the column as clearly shown in Figs. 10 and 11. I prefer to arrange the parts so that the joint 24 will come approximately at one corner of the column, and it will be noticed, by referring to Fig. 10, that the abutting ends of the furring strips 2b are arranged in lapped relation as at 25. This lapping is made possible by virtue of the fact that the width of the clips 5 on the furring strips is substantially less than the loops 6 beneath which they are engaged, and by simply offsetting the furring strips in the loops they can be made to lap past each other as described.

A column form is positioned around its column in much the manner already described for the girder form, except that the positioning must take place in two directions. At intervals vertically along the column 23 are provided the positioning strips 26 which are secured to the flanges of the column by means of the clips 27 in the manner already described for the girder form, the ends of the strips 26 being pressed or distorted to fit within the legs of the U-shaped furring strip 2b as at 28. It is not necessary to use strips 26 at every furring strip 2b, but for all average column heights one such strip 26 may be introduced in every third or fourth furring strip. In the other direction strips 29 may be employed and secured with respect to the column flanges in any similar or other desired manner, with their ends also projecting into the furring strips 2b as at 30.

After the column forms are in place, the gypsum 14 is poured in plastic condition as already described in connection with the ceiling and girder construction, and the coating of plaster 15 subsequently applied to the outside.

It will be seen that I have devised an extremely simple system for fireproofing buildings, and that the essential features of the invention may be applied throughout, namely, to the ceiling, to the girders, and to the columns. In pouring the gypsum I prefer to place all of the forms for the ceiling, girders and columns in any given section of a floor of the building, and then pour the gypsum all at one time, the pouring, of course, taking place from above. After the fireproofing has been applied, the floor 31 of concrete may be poured, the floor form 32 having been placed in position first.

This floor form consists of metal lath similar to the form plate used in constructing the ceiling, but not necessarily provided with the furring strips used in connection with the ceiling. It should be noted that the top cords

of the joists may be provided with upstanding pegs 33 adapted to puncture the lath 32 when the latter is being placed in position over the joists. These pegs serve to position 5 and hold the lath and also to support the top cord of the joist laterally, because they subsequently become incorporated in the poured floor slab. Material other than concrete may, of course, be used for the floor if desired.

10 I wish to direct particular attention to the fact that by means of my improvements it is possible to erect forms without the necessity of employing skilled labor, the assembly of the lath and furring strips, and the subsequent bending, where necessary, and positioning, being extremely simple operations which can be carried out by workmen of average qualifications. Expensive wooden forms which must only be torn down after the fire- 15 proofing has set are dispensed with, and the form which I do employ becomes an integral part of the structure and serves to protect or armor the gypsum.

20 At the time of pouring the ceiling fireproof- 25 ing slab and before the gypsum has obtained its set, I prefer to straighten the under side with a straight edge so that the finished slab is perfectly straight, thereby presenting a surface for applying the plaster which becomes unusually efficient because of the straightness and because of the admirable 30 key provided by the type of the form plate and the projection of a small amount of gypsum at each loop opening. This makes 35 it possible to produce perfectly satisfactory results with a one or two coat finish of plaster instead of the customary two or three coat finish.

I claim:—

40 1. In building construction the herein described method of covering a structural member which consists in laying out metal lath in flat position, in securing furring thereto, in bending the assembled lath and furring 45 into a self-centering form of the shape desired, in applying the form to the structural member, and in pouring an inner fill of plastic material.

2. The herein described method of fire- 50 proofing the structural work of buildings which comprises laying out form plate or metal lath in flat position, in securing furring thereto, in bending the assembled plate and furring into a self-centering form of the 55 shape desired, in applying said self-centering form to the work, and in pouring an inner fill of fireproofing.

3. In the fireproofing of ceiling structures, the method which comprises laying out form 60 plate or metal lath in flat position, in securing furring thereto, in suspending said assembly by said furring from said structure, and in pouring an inner fill of fireproofing.

4. A fireproof coating including, in combination, an outer metallic form plate, spaced

rows of inwardly projecting loops and inwardly projecting corrugations between the rows of loops, attaching furring secured to loops transversely of the rows, and an inner fill of gypsum.

5. In fireproof building construction, the combination of an outer metallic form plate, inwardly projecting rows of loops pressed out of the metal of the plate, inwardly projecting corrugations between the rows of loops, attaching furring secured to the loops, and an inner fill of gypsum.

6. The method of fireproofing the structural work of buildings, which comprises placing a self-centering metal form adjacent the structure, pouring thereon an inner fill of fireproofing material, and in straightening the exposed surface while the fill is still plastic.

7. In the fireproofing of ceiling structures, the method which comprises laying out form plate or metal lath in flat position, in securing furring thereto, in suspending said assembly by said furring from said structure, in pouring a fill of fireproofing thereon, and in straightening the exposed surface while the fill is still plastic.

8. In building construction the method of covering structural work which comprises laying out form plate or metal lath in flat position, in fastening furring thereto, in securing said assembly to the structural work, and in pouring an inner fill of fireproofing.

In testimony whereof I have hereunto signed my name.

GEORGE F. PAWLING.
